UNITED STATES PATENT OFFICE.

ALBERT L. PARCELLE, OF BOSTON, MASSACHUSETTS, ASSIGNOR TO THE NATIONAL ELECTRICAL COMPANY, OF NEW YORK, N. Y.

ELECTRICAL SYNCHRONOUS MOVEMENT.

SPECIFICATION forming part of Letters Patent No. 324,153, dated August 11, 1885.

Application filed October 4, 1884. (No model.)

To all whom it may concern:

Be it known that I, ALBERT L. PARCELLE, of Boston, in the county of Suffolk and State of Massachusetts, have invented an Improved 5 Electrical Synchronous Movement, of which the following is a specification.

Such movements are capable of various uses, and of course I contemplate employing my invention wherever the synchronous movement 10 of electrically-connected apparatus is desired. An important field for such an invention is that of multiplex telegraphic transmission of messages, and I have therefore, as one application of my invention, shown ordinary telegraphic keys and relays connected with insulated contacts, over which circuit-completers carried by the synchronously-moving apparatus pass. Of course any other suitable 15 telegraphic apparatus other than those of the character shown may be used.

I am aware that numerous arrangements for obtaining synchronous movements have been heretofore patented. My invention, however, differs from all such systems, both in its general 20 principles of operation as well as its details of organization.

In the accompanying drawings, Figure 1, 1^a is a diagrammatic view illustrating two stations, X and Y, connected by a main line and 25 equipped according to my invention. Fig. 2 is a detail view, partly in section, illustrating the motor which I prefer to employ in working my system; and Figs. 3 and 4 are diagrams showing the traveling arms in varying positions.

In Fig. 1, 1^a, two stations, X and Y, are shown connected by a main line. The organizations at both stations are identical, and are as follows:

40 A vibrator, A, mounted at one end in a block or post, A', carries an armature, a, arranged transversely on its free end and acted upon by magnets B C, having the faces of their poles opposite the face of the armature and in a plane substantially parallel therewith. Contacts b c on opposite sides of the vibrator make contact with spring-fingers b' c' in the circuit of the motor-magnets B C, to make and break the circuit, as is well understood. In 45 addition to these contacts, I also employ switch

devices D, which may be constructed as follows: A sliding block, E, is mounted on a suitable bed-plate, the sliding block being guided and limited in its movement by two screws, e, which pass through slots in the block and are 55 secured to the bed-plate. Two uprights or posts on the sliding block are provided with adjusting-screws e', between which the vibrator A is located. As the vibrator moves, therefore, the sliding block is shifted first to 60 one side and then to the other, and the exact moment of its movement may be regulated in a measure by the adjusting-screws e'. These screws may be tipped with rubber or cork to prevent noise.

65 The sliding block carries two contact-fingers, F G, (either insulated or uninsulated from each other,) which make and break contacts with posts f g as the vibrator moves back and forth and shifts the switch-block. One 70 pole of the motor-battery LB is connected with the heel of the vibrator. From thence the circuit is continued through the vibrator to the platinum contacts b c, thence by either of the springs b' or c' through the coils of either 75 of the magnets B or C, and thence to either of the contact-fingers F or G and contact-post f or g to the opposite pole of the battery. These circuits are shown in the drawings by dotted lines. The circuit of the magnet B is 80 represented by the letter b', and that of the magnet C by the letter c'.

In starting the motor into operation an impulse of vibration may be imparted to it by the hand of the operator. Assuming that the 85 vibrator is moving toward and across the faces of the poles of the magnet C, the contact c will make contact with the finger c' while the contact-finger G of the switch devices is on the contact-face of the post g. The circuit, therefore, 90 will be completed from the battery LB through the vibrator, contact c, finger c', coils of the magnet C, and thence by wire c' to the finger G, post g, and opposite pole of the battery, and the armature a will be attracted. The 95 continued movement of the vibrator in that direction opens the circuit just described by the shifting of the sliding block E, which moves the finger G out of contact with the post g, and makes contact between the finger 100

F and the post f in the circuit of the opposite magnet B. The vibrator will now by its resilience spring back and make contact between the contact-plate b and the finger b', thus completing the motor-circuit through the coils of the magnet B. Under the attraction of the magnet B the vibrator continues its movement until by the shifting of the block E the circuit of said magnet is opened at the contacts F f.

10 I utilize the vibrating motor just described to actuate circuit-completing devices in the following manner, (see more especially Fig. 2:) The vibrator is there shown as rocking an anchor-lever, H, back and forth in its vibration. This lever is shown as pivoted in a horizontal arm, H', of a standard, H², mounted on the bed-plate. The lower end of the anchor-lever on which the vibrator acts is notched, and is preferably provided with elongated lateral extensions h, which serve as guides or guards to prevent the vibrator swinging free of the anchor-lever, and thus insure its proper actuation. Pitmen or push-and-pull arms H³, pivoted on the anchor-lever, 20 carry pawls or teeth, which work in a ratchet-wheel, H⁴, having its bearing in the standard H². The rocking of the anchor-lever by the vibrator causes, therefore, an intermittent or step-by-step rotation of the ratchet-wheel. A 25 circular table, I, is carried by the standard H², and is supported thereon concentrically with the axis of the ratchet-wheel H⁴. The axle of the ratchet-wheel passes through the table, and carries on its outer end an arm, K, 30 which extends across the table I, and is provided at one end with a trailing brush or finger, k, which traverses around the table. A circular series of independent contacts are arranged upon the table in the path of the 35 brush k, which makes contact with them successively.

In Fig. 1, the organization above described is illustrated properly connected at the upper part of the figure at each station, while the lower part of the figure diagrammatically represents the table, the trailing circuit-completer, and the electrical devices and circuits of my improved synchronous arrangement.

The vibrator-motor which I have described is one well adapted for the actuation of my synchronous movements; but I do not confine myself to its use, nor is any claim herein made to the motor *per se*, as it constitutes the subject-matter of another application filed by me

55 September 1, 1884, and numbered 141,952.

In electrical synchronous systems heretofore patented it has been proposed to actuate the apparatus independently at each station and to correct the speed of the motive apparatus at one station by means of an impulse of electricity transmitted from the distant station. Though I employ an independently-actuated motor at each station, the correction, should the apparatus at one of the stations move too fast, is accomplished locally by said apparatus itself, though the effect of such correction is removed by an impulse of elec-

tricity from the distant station, and this feature constitutes one of the peculiar characteristics of my invention.

On the table I at each station I have shown four contacts devoted to maintaining the synchronous movement of the apparatus at the two stations. Two of these contacts (marked m m') are placed one on each side of the table, though not directly opposite each other, and are connected to earth by a wire, m², through the coil of a magnet, M, as clearly shown. The other two contacts, n n', also arranged on opposite sides of the table, about midway between the contacts m m', though not directly opposite each other, are connected together, and by a line, n², with a main battery, MB. The arm K, which carries the brush or circuit-completer k, extends entirely across the table of contacts, and is shown as projecting slightly beyond the table at each end. It is so shaped that a straight line drawn from the end k' to the end which carries the trailing-finger would not be a true diameter of the circle of the table of contacts, but the end carrying the trailing-finger is deflected from a true diameter, the direction of the deflection being toward the end of the trailing-brush k. This is done so that in the operation of the apparatus the end of the trailing-finger will make contact at the proper time with the plates m m' and n n', which are placed at irregular intervals around the table, as is fully described below.

A detent, O, lies normally in the path of the extended ends of the arm K, as clearly illustrated in the drawings. This detent preferably consists of an elastic or spring arm, which is mounted and slides in a suitable frame, P, for the purpose presently described, and carries an armature, o, which is acted upon, as will be described, by the magnet M. The detent-arm O is constructed with a guide-pin, which slides in an eye in the frame P, and is provided with a coiled spring, o', which tends normally to press the arm outwardly from the frame in the direction of the magnet M. The detent O between the arms of the frame P is provided with an enlarged face or plate, o², which, when the detent is thrust back by the impact of the arm K, as shown at X in Fig. 1, makes contact with two adjustable contact-pins, c⁴ and b⁴, mounted in but insulated from the frame P. The contact-pin c⁴ is connected by a line, c³, with the circuits c² of the magnet C at a point between the coils of the magnet and the contact-finger G in said circuit, and by a line, b³, with the circuit b² of the magnet B. The pin b⁴ is connected by line q, key Q, and its back stop, through the coil of the magnet M, to earth, as clearly shown in the drawings. The front stop of the key is connected, as shown, with the main battery MB. Another insulated contact-pin, r, mounted on the leg of the frame P opposite that which carries the pin c⁴, is connected with the arm K, as clearly shown. When the detent O is pushed back by the end

of the arm K abutting against it, as shown in the drawings, (Fig. 1, station X,) it makes contact by means of its plate o^2 with the two pins c^4 and b^4 , and when the detent is not in engagement with one of the ends of the arm K its contact-plate o^2 is pressed by the spring o' toward the opposite leg of the frame P into contact with the insulated contact-pin r , (station Y, Fig. 1,) which is connected directly with the arm K, as before mentioned. The pole of the local battery LB which is not connected with the heel of the vibrator is connected, as shown, by a line, lb , with the frame P. The main line L, connecting the stations, is also connected at each end with the frame P, and the frame is electrically connected with the detent O, which is carried by it. This construction is well adapted for the purpose and the various connections properly made; but of course my invention is not limited to such details. The purpose of these various connections will now be described.

When the contact-plate o^2 of the detent O is in the position shown in the drawings at X, Fig. 1, one or the other of the local motor-circuits b^2 or c^2 will be completed around and outside of the switch devices D, so that the circuit which happens to be completed at the points b^2 or c^2 will remain closed as long as the detent remains in the position illustrated, and the vibrator will be checked or held up toward the magnet, B or C, the circuit of which is completed, as just stated. For instance, if the vibrator has swung to the right, as viewed in the drawings, and makes contact between its plate c and contact-finger c' , the motor-circuit of the motor C will be completed as follows: from the local battery LB through the vibrator, contacts c^2 , coils of the magnet C, line $c^2 c^3$, pin c^4 , contact-plate o^2 of the detent, frame P, and by line lb to the opposite pole of the battery; and as long as the circuit remains closed at the pin c^4 the vibrator will be held on that side of the center of vibration and prevented from swinging back toward the magnet B. The same operation would occur if the vibrator happened to be in a position to make contact between b and b' , and the vibrator would be held up by the magnet B. By this means I am enabled to check or retard the speed of the vibrator to insure the synchronous movement of the apparatus, as will more fully appear presently. When the contact-plate o^2 is pressed out (which is the normal position) by the spring so as to break contact with c^4 and b^4 , of course the shunts around the switch device D are opened and the motor operates as before described. When the contact-plate o^2 of the detent O is in contact with the main-line pin r , which is the normal position when the apparatus at the two stations is running synchronously, the main-line circuit will be completed from one station to the other through the frame P, contact-plate o^2 , pin r , and radial arm K to the contacts or space between the correcting-contacts m^2 and n^2 , and may be used for any purpose desired.

Whenever either end of the arm K has abutted against the detent O, as shown in the drawings, the end of the trailing-finger k will be on one of the ground-contacts m^2 . For instance, take the position shown at X in Fig. 1. There the brush end of the arm K has abutted against the detent O, and the end of the trailing-finger k is resting on the ground-contact m^2 . In this position the main-line circuit is completed through the frame P, detent O, arm K, ground-contact m^2 , and coil of the magnet M to earth. When the opposite end of the arm is against the detent, the finger k will make contact with the other ground-contact, m , and the circuits are the same as just mentioned. If, therefore, an impulse be received from the distant station with the arm in either of the two positions mentioned, the magnet will be energized and the detent drawn down out of the path of the pin. With the parts as shown at Fig. 1, station X, the vibrator, when vibrating, will be checked or held up at one side of its stroke, as before mentioned, so that all the parts at that station will be checked.

Assuming, now, that the apparatus at the two stations is running, and that the arm K at station X is a little in advance of the arm at Y, so that the end of the arm carrying the brush at X has pushed back the detent O at that station before the trailing-brush k at station Y has come upon the battery-contact n^2 , under these conditions one of the motor-circuits b^2 or c^2 will be completed, as before described, according to whether the vibrator is moving up or down, as viewed in the drawings, and has made contact with either spring b^2 or c^2 . The effect of such a completion is to hold up the vibrator on one side and check all the apparatus at station X to retard its motion. As the brush k at station Y comes upon the battery-contact n^2 , an impulse of electricity from main battery MB will be transmitted through wire n^2 , contact n^2 , trailing-brush, arm K, pin r , over the main line, and at station X through the frame P, pin b^4 , wire q , key Q, and coil of magnet M, to ground. By this impulse, therefore, the magnet M will be energized, and, attracting the armature o , will draw the spring-detent O out of the path of the end of the arm K. The spring o' will force the contact-plate out of contact with the pins c^4 and b^4 , the check or brake on the motor will be removed, and it will start into operation to again rotate the radial arm K. At the same time the main-line circuit is completed, as described, by the plate o^2 making contact with the pin r at station X. When this operation occurs, the arms at both stations will continue to move in their proper respective positions—that is to say, the brush k at station Y will leave the battery-contact n^2 at the moment the brush k at station X leaves the ground-contact m^2 . If they continue to move at the same speed, by the time the brush end of the arm at station Y has reached the detent O and is about to strike it, the brush k at station X will come upon the battery-con-

taet n , and an impulse of electricity will be transmitted, in the manner before described, from station X to station Y to remove the detent O from the path of the arm K. Should 5 the arm K at station Y move more rapidly than the arm at station X during the portion of their revolutions just described, it will strike the detent, the parts will be thrown into the same positions as indicated at X, and the 10 motor at Y will be checked in the manner already described, and when the brush at station X comes upon the battery-contact n the detent will be thrown out of the path of the arm at station Y, so that the arms at both stations 15 can again start together. The same operation occurs when the end k' of the arm at X upon its further movement reaches or strikes the detent O, and the brush k at station Y comes upon the battery-contact n . Thus 20 as long as the apparatus at the two stations is running synchronously the detents O will be withdrawn from the paths of the traveling arms just at the proper moment, and this will occur alternately, two such impulses being sent 25 from Y and two from X during each revolution of the arm K; but should the apparatus at one station run ahead of that at the other the end of the arm K would strike the detent before it had been removed by the impulse of electricity 30 received from the distant station and the speed of the accelerated apparatus checked.

When the end of the arm K strikes the detent O, the detent yields and the arm follows it for a short distance. Aside from the other results 35 accomplished by this movement, the yielding of the detent permits the contact finger or brush k to move over part of the ground-contact m or m' , and when the finger k at the other station first comes upon the battery-contact 40 at that station the arm abutting against the detent will be slightly in advance of its proper position at the moment the impulse of electricity is transmitted to release it. This gives a period of time for the transmitted impulses to act, and also gives an allowance for 45 the inertia of the arm at rest, so that by the time it commences to move it occupies the proper relative position to the other arm. The extent of this movement may be varied by adjusting the contact-pins c' b' r .

During the period that the contact-fingers k at each station are traversing the circles of contacts between the ground and battery contacts the main line is completed from the 55 brush at one station to the brush at the other station, and is entirely free for any purpose for which it may be desired.

As before remarked, the ground-contacts m and the battery-contacts n n' are not immediately opposite each other, and the table of contacts is not divided into four equal sections by these contacts. For instance, the table at station X has twenty-four contacts between the battery-contact n and the ground-contact m . There are twenty-seven between the ground-contacts m and the battery-contact n' , thirty between the battery-contact n'

and the ground-contact m' , and twenty-seven between the ground-contact m' and the battery-contact n . At station Y the four sections into which the table is divided are proportioned in the same way, but they do not occupy the same relative position. There are twenty-seven contacts between n and m , thirty between m and n' , twenty-seven between n' and m' , and twenty-four between m' and n . When the arms K are moving synchronously, however, each arm has to travel over the same number of contacts to reach its respective ground or battery contact. This will clearly appear by reference to the drawings. Of course the spaces between the battery and ground contacts need not be divided in the manner illustrated, or in any particular manner so far as my synchronous movement is concerned; nor do I limit myself to the particular irregular arrangement illustrated of the battery and ground contacts in the circle. The irregular arrangement, in connection with the deflection of the arms K, removes the detents at irregular intervals in the circle of rotation, and therefore, though the arms K may not start in the proper relative position, they will in a few moments, by the alternating impulses, be brought into the proper relation and caused to rotate synchronously.

By arranging the contacts at irregular intervals a correction can take place oftener than once in a revolution. Should the arm be started and the contacts placed at regular intervals, one arm might be half a revolution ahead of the other, and still both the machines would run, because the detent would be removed at the half-revolutions; but the machines would not be synchronous. If more than one correction is to take place in a revolution, the contacts should therefore be placed at irregular intervals in the circle and the rotating arm deflected to conform to such irregularity. Again, the irregular arrangement of contacts makes the apparatus self-synchronous when they have been started into operation.

The magnet M is shown and described as located directly in the main-line circuit, and this is perhaps as good an arrangement as any on short lines. When desired, however, an ordinary line-relay may be used to work the magnet M locally.

When the apparatus is running, the impulses of electricity alternately sent from one station to the other occur periodically when the finger k comes on a battery-contact at the sending-station. Such impulses always act on the detent at the distant station to either move it out of the path of the arm K before or after said arm comes in contact with it. The correcting-checks which act on the motor that is moving too rapidly are entirely local, and occur, as described, when the rotating arm K abuts against the detent O, and thus closes the shunts of the local battery around the switch D in the motor-circuits. Theoretically the rotating arms are checked or stopped to correct the speed of the motor; but practically such

checks, when they do occur, occupy such a brief period of time that their effect on the apparatus cannot be detected. If, therefore, telegraph-instruments were connected at each 5 station with a number of corresponding contacts, as is contemplated in this class of apparatus, the operators would not be aware of the correcting-checks. I have shown fifteen teeth in the ratchet-wheel H^4 , actuated by the 10 motor; and if the vibrator makes thirty vibrations per second, the arm K will rotate over the table of contacts twice in a second—a speed suitable to such a table of contacts, as shown. Of course any other rate of vibration 15 and any other number of teeth in the ratchet may be adopted.

Where the circle of contacts is large, or the speed of rotation rather rapid, or where the distance from one station to the other is great, 20 of course the width of the ground and battery contacts may be increased so as to give a proper duration of ground and battery connection for the effectual transmission of the impulses.

In describing the synchronous operation of 25 my improved apparatus I started with the assumption that the arm at each station was running. If the arms at the two stations were at rest, with the brushes on the ground-contacts m or m' , and with the detent in the normal position indicated at Y in Fig. 1, then the operator at either station could call the operator at the other station by pushing the plate o^2 of the detent back into contact with the pin b^4 , for then a depression of the key Q at that 30 station would transmit an impulse of electricity from the battery MB, through said pin, detent-plate, and frame P, over the main line, to the distant station, where it would pass by way of the frame P, detent-plate, contact r , to the 35 arm K, its brush, and ground-contact, through the coil of the magnet M, to ground. The magnet being thus energized would attract the detent-armature o against its pole, and call the attention of the operator. In this way the 40 operators may be called up and the apparatus started whenever desired.

In starting the apparatus the arms may start in any position in which they happen to be when the respective motors are thrown into 45 action by the operators. They will, however, as before remarked, by the alternate corrections, be brought into proper position for synchronous operation—that is, into the position illustrated in Fig. 1. Assuming, for instance, that the arms start in about the positions indicated by the full lines in Fig. 3, then they would travel until the ends k' of the arms abut against the detents, as indicated by dotted lines in Fig. 3, and stop the apparatus at 50 both stations, as before described. Then, if the operator—say at station Y—releases the arm and throws the motor into operation by depressing the detent, the arm at that station will commence to move in the direction of the 55 arrow, and when it has traveled over the table to the first battery-contact, n' , as shown at Y, Fig. 4, an impulse of electricity will be sent

from the battery MB at station Y, through the wire n^2 , contact n' , arm K, contact-pin r , plate o^2 of the detent, and frame P, over the 60 main line, to station X, where the current passes through the frame P, contact-plate o^2 , pin b^4 , and key Q, through the coil of the electro-magnet M, to earth. This energizes the magnet M, and the detent O at station X is 65 drawn out of the path of the end k' of the arm K, which commences to rotate from the position indicated at X, Fig. 4, at the same time that the brush k at station Y leaves the contact n' . If the apparatus is running synchronously now, the brush k at station X will reach the battery-contact n' at the same moment that the brush at station Y reaches the ground-contact m' , and, as described, the detent will be 70 removed from the path of the latter brush. If, however, the arm K at Y moves ahead of the arm at X, it will be stopped by the detent and the speed of its motor checked, as has been 75 fully explained. No matter in what positions the arms may be started with relation to each other, the apparatus at the stations will be alternately corrected until the arms are brought into the proper positions shown in Fig. 1.

If the apparatus at the two stations is at 80 rest, with the arms K pressing against the detents so as to force them back against the pins c^4 b^4 , of course the operator at either station may release the arm at that station by depressing the detent, as before mentioned; 85 but if, in addition to these conditions, the vibrators of the motors are drawn to one side, so as to close either of the shunts b^2 c^2 , then the operator at either station, by the depression of his key Q, may release the motor and 90 apparatus at the distant station and start it into operation, as already described.

When either of the apparatus has been 95 started, it will transmit its releasing impulse to the distant station to remove the detent from the path of the arm at that station, and then by the alternate corrections described the arms at both stations will be brought into 100 proper synchronous relation.

It will be observed that the width of the 105 ground and battery contacts, the length of the brush k , the deflection of the arm K, and the amount of movement of the detent are so proportioned that the brush will come upon the ground-contacts before it moves the detent 110 back, and will still be upon the ground-contact after the detent has been thrust entirely back. The purpose of this arrangement is, that if the arms are running synchronously the impulse 115 from the battery-contact at one station to the ground-contact at the other will pass and energize the magnet M before the detent has been pushed back, so that it will be removed from the path of the arm without stopping it. This will appear clear from Figs. 1, 3, and 4. 120

I have indicated in the simplest diagrammatic manner at each station, merely by way of illustration, three telegraphic keys, S, and relays T, each connected with a contact on the 125

table of contacts. The relays are all preferably grounded by wires through the coil of the magnet M. The front stops of the keys are connected through a resistance, R_h , by wire t, with 5 the main battery MB. I have shown each key connected with one contact only; but of course any desired number of the independent contacts may be connected with each set of 10 telegraphic instruments, as is now well understood by those expert in this matter. The operators at one station may telegraph to the corresponding operators at the other over the interrupted circuit which is given in rapid 15 succession to each pair of operators as the arms 15 K synchronously rotate.

The resistances R_h are introduced in the telegraph-lines for the following purpose: If the full power of the battery MB were sent 20 into the line by the manipulation of the keys S, such telegraphic impulses would also energize the magnet M at the distant station, and might move the detent O at an improper time. By introducing the resistances and making the detents O of a tension to resist the power 25 of the magnets except when energized by the full power of the batteries MB, such an action is prevented.

The relays T are preferably grounded, as shown, through the magnets M, so that in case 30 the apparatus is not in proper position to receive the regularly-transmitted impulses sent to release the detent—as, for instance, if plate a^2 of detent did not make contact with its pin b^2 —the operator, by working the key Q at the 35 distant station, may send an impulse of the full power of the battery MB through one of the telegraphic contacts and relays at the station receiving the impulse. This arrangement is not, however, deemed necessary.

40 It will perhaps be found best on long lines to ground the line at each end between the contacts by inserting supplementary contacts in the circle, as is now well understood and set forth in sundry patents.

45 The particular motors illustrated are, in my opinion, specially adapted to this synchronous system. They can be adjusted so that two of them can be made to run at speeds so nearly equal to each other that only occasional corrections of the apparatus are required, and, of course, the more equality of speed the greater will be the efficiency of the apparatus.

50 As before remarked, this invention is not limited to the particular motor, nor to other specific details of construction and organization 55 so far as the broader principles of the invention are concerned, as electrical engineers may readily devise other apparatus to work on the same principle.

60 The table of contacts shown in the drawings is larger in proportion to the size of the motor than I prefer to construct it. The parts would be more accurately proportioned if the vibrator of the motor were twice the length and thickness shown, and for such a sized motor I prefer to make the vibrator about an inch in width. 65 This size is one which I have found to work

well at the rate of thirty vibrations per second.

The two parts of Fig. 1 are placed on separate sheets, so as to show a large circle of contacts and bring out the operation more clearly.

As viewed in the drawings, Figs. 1 and 1^a, the contacts are preferably so located on the circular table that when it is divided into quadrants by drawing vertical and horizontal lines through its center, such lines will pass between adjacent contacts and not through any of them.

80 I claim as my invention—

1. The combination of the main line, independently-actuated vibrators at each end of the main line, rotating apparatus at each end of the line controlled by said vibrators, local 85 correcting devices at one end of the line for correcting the speed of the vibrator and apparatus at that station solely by their own action, and means by which a current of electricity is transmitted over the line to release or free the 90 vibrator and apparatus from said correcting action.

2. The combination of the main line, independently-actuated vibrators at each end of the main line, rotating apparatus at each end of the main line controlled by said vibrators, local 95 correcting devices at each station for correcting the speed of either vibrator when it runs out of time with the other solely by the action of the correcting devices at the particular station, and means by which currents of electricity may be sent from either 100 station to the other to release the vibrators from said correcting action.

3. The combination of a main line, independently-actuated apparatus at each end of the main line, a vibrator at one end of the main line for controlling the apparatus at that station, correcting devices by which the vibrator is automatically corrected at said 110 station solely by the action of the correcting devices at that station when the apparatus at said station runs out of time with the apparatus at the distant station, and means for transmitting a correcting impulse of electricity 115 over the line to release or free the vibrator from said correction.

4. The combination of a main line, independently-rotating apparatus at each end of the line, a vibrator at one station for actuating or controlling the apparatus at that station, a local circuit for correcting the action of the vibrator, means by which the rotating apparatus at the vibrator-station completes said 120 correcting-circuit when the apparatus runs out of time with the apparatus at the distant station, and means for transmitting an impulse of electricity over the line to release the vibrator from said correcting action when the apparatus at the two stations come 130 into proper relative position.

5. The combination of the main line, an independently-actuated vibrator at each end of the line, rotating apparatus controlled by said

vibrators, a local circuit at each station for correcting the speed of the vibrator, means at each station for completing said local circuit whenever the apparatus at either station 5 runs out of time with that at the distant station, and means for transmitting a current of electricity over the line to release either of said apparatus when both apparatus come into corresponding positions.

10 6. The combination of a main line, a table of contacts and a rotating arm which traverses said table at each end of the main line, a detent or circuit-changer located in the path of said traveling arm at one station, with which 15 said arm makes contact when it runs ahead of the other arm at the distant station, and electric devices for transmitting a current of electricity from the distant station to separate said arm and circuit-changer when the two 20 apparatus come into corresponding positions, for the purpose set forth.

7. The combination of the main line, the independently-actuated apparatus at each end of the main line, synchronously-rotating devices actuated by said apparatus, a detent or 25 circuit-changer located in the path of said rotating apparatus at each station, and a local circuit at each station thrown into operation by said detent or circuit-changer to control 30 the speed of the independently-actuated apparatus at that station.

8. The combination of the main line, independently-actuated apparatus at each end of the main line, synchronously-rotating devices 35 actuated by said apparatus, a detent or circuit-changer at each station, which normally lies in the path of said rotating devices, a local circuit at each station for controlling the independently-actuated apparatus, which circuit is thrown into operation whenever the 40 synchronously-rotating devices come in contact with said detent, and electro-magnetic devices for periodically and alternately removing the detent from the path of the rotating apparatus at each station by means of 45 an impulse of electricity transmitted from the distant station.

9. The combination of a main line, independently-actuated apparatus at each end of 50 the main line, synchronously-rotating devices actuated by said apparatus, the circuit-completer or trailing-finger at each station, normally connected with the main line, a table of contacts over which said finger traverses, a 55 detent or circuit-changer normally located in the path of the rotating devices at each station, a local circuit at each station controlled by said circuit-changer for correcting the speed of the independently-actuated apparatus, 60 and the battery and ground contacts at each station.

10. The combination of a main line, synchronously-rotated apparatus at each end of the main line, trailing-fingers or circuit-completers carried by said rotating devices, a table of contacts at each station, over which said circuit-completers traverse, means, substan-

tially such as described, for maintaining the synchronous rotation of said devices, and the ground and battery contacts placed at irregular intervals in the table of contacts at each station. 70

11. The combination of the main line, synchronously-actuated apparatus and a table of contacts at each end of the main line, rotating arms having circuit-completers which traverse said tables of contacts, actuated by said synchronously-moving apparatus, said rotating arms occupying positions when moving synchronously substantially at right angles to each other, the ground and battery contacts placed at irregular intervals in the table of contacts, and means, substantially such as described, for maintaining the synchronous movement of the apparatus at the two 85 stations.

12. The combination of the main line, rotating apparatus at each end of the main line, a detent in the path of the rotating apparatus 90 at each station, and means, substantially such as described, for alternately removing said detents from the paths of the rotating apparatus, to insure their equal and uniform movement.

13. The combination of the main line, rotating apparatus at each end of the main line, 95 a detent or circuit-changer in the path of the rotating apparatus at each station, with which either of said rotating apparatus makes contact to correct its speed only when it runs ahead of the other apparatus, and means, substantially such as described, for alternately removing said detents from the paths of said rotating apparatus, substantially as set forth. 100

14. The combination of the main line, the rotating apparatus at each end of the main 105 line, a detent in the path of said rotating apparatus at each station, ground and battery contacts at each station, over which a circuit-completer on the rotating apparatus moves, and electric circuits and devices for alternately and periodically removing said detent from the path of the rotating apparatus at each station. 110

15. In a synchronous system of electrical movements, substantially such as herein described, the combination of rotating circuit-completers, a table of contacts over which said circuit-completers move, and ground and battery contacts placed at irregular intervals in 115 said tables of contacts. 120

16. The combination of the main line, the independently-actuated vibrator at each end of the main line, the motor-magnets, circuits, contacts, and switch devices of each vibrator, shunts around the switch devices in the circuits of the motor-magnets, the synchronously-rotating devices actuated by said vibrators, a detent or circuit-changer located in the path of said rotating devices at each station, contacts by means of which said circuit-changer or detent closes the shunts in the motor-circuits whenever the rotating devices at 125 one of the stations comes in contact with the detent, and means, substantially such as de- 130

scribed, whereby the detents are periodically alternately removed from the paths of the rotating devices.

17. In a system of synchronous movement, substantially such as herein described, the combination of the rotating arms, the yielding detents, and the ground and battery contacts.

18. The combination of the main line, rotating apparatus at each end of the main line, a yielding detent in the path of the rotating apparatus at each station, and means, substantially such as described, for alternately removing said detents from the paths of the rotating apparatus.

19. In electrically-connected rotating apparatus, the combination of the rotating arm and the yielding detent for acting on said arm, for the purpose set forth.

20. The combination of the main line, synchronously-rotating apparatus at each end of the main line, a detent in the path of the rotating apparatus at each station, electro-magnets for removing said detents from the paths of said rotating apparatus, and a key and battery at each station for transmitting an impulse of electricity to the distant station for removing the detent from the path of the rotating apparatus.

In testimony whereof I have hereunto subscribed my name.

ALBERT L. PARCELLE.
